Primary Examiner — Cynthia R Underwood(74) *Attorney, Agent, or Firm* — Vierra Magen Marcus LLP(57) **CLAIM**

The ornamental design for handles for a tablet computer enclosure, as shown and described.

DESCRIPTION

FIG. 1 is a front perspective view of handles for a tablet computer enclosure.

FIG. 2 is a front elevation view the handles for a tablet computer enclosure.

FIG. 3 is rear elevation view of the handles for a tablet computer enclosure.

FIG. 4 is a top view of the handles for a table computer enclosure. A bottom view of the handles for a table computer enclosure is a mirror image of FIG. 4.

FIG. 5 is a right side view of the handles for a table computer enclosure. A left side view of the handles for a table computer enclosure is a mirror image of FIG. 5; and,

FIG. 6 is front perspective view of the handles for a tablet computer enclosure, attached to an exemplary tablet computer enclosure.

In FIGS. 1-5 of the drawings, the broken lines represent unclaimed portions of the claimed design and form no part of the claimed design.

In FIG. 6 of the drawings, the broken lines depict unclaimed environment and form no part of the claimed design.

1 Claim, 5 Drawing Sheets(56)
